CHAIR

Julius L. Cable, Boston, Mass.

Application November 15, 1933, Serial No. 698,028

8 Claims. (Cl. 155—50)

This invention relates to improvements in chairs. More especially it relates to chairs having a frame made up primarily from metal.

So-called modernistic tubular steel chairs usually have a steel rod or tube on each side at the front to form the legs. At the level of the seat these rods bend rearward to form side supports for the seat and then bend upward to form supports for the back. While this construction is slightly flexible, chairs so made can not properly be described as comfortable as there is no appreciable yield to the frame.

It is an object of the present invention to so bend and arrange a continuous tubular metal frame member as to produce a chair which is notably yielding and really exceedingly comfortable. It is a feature of the invention that it can be applied to chairs of various types, as for example a simple chair, an office chair which can rotate and tilt with respect to its base, a chair having a tilting back, a hospital or wheel chair, and so on. The same features of the yieldable frame can be incorporated in a chair in which the frame is for the most part fully exposed or they may be applied to chairs in which the frame is mostly concealed by upholstering.

The best mode in which I have contemplated applying the principles of my invention is disclosed in the accompanying drawings but these are to be taken as merely illustrative because it is intended that the patent shall cover by suitable expression in the appended claims whatever features of patentable novelty exist in the invention as a whole.

35 In the drawings:

Figure 1 is a side perspective showing a chair embodying the present invention;

Figure 2 is a front perspective of the same chair with parts cut away for disclosure of details;

40 Figure 3 is a side view of the chair of Figures 1 and 2;

Figure 4 is a similar view showing a slight modification;

Figure 5 is a bottom perspective showing how the seat plate engages the frame members;

Figure 6 is a side perspective of an office chair embodying the present invention;

Figure 7 is a vertical median section of the said office chair;

50 Figure 8 is a side perspective of a chair embodying the present invention and provided with an adjustable back;

Figure 9 is a vertical section, as on line 9—9 of Figure 10, through the arm of the chair of Figure 8; and

Figure 10 is a side elevation in vertical section on line 10—10 of Figure 9.

Referring now more particularly to the drawings, and especially to Figures 1 to 3, the important features of my present invention can best be appreciated by considering the vertical side view of the chair shown in Figure 3. As here shown, each side member A of the frame is composed of a single continuous spring-steel rod. Starting from the bottom or rear end of this rod 65 it has a short vertical section 10, constituting a rear leg as it were, then a horizontal section 12 which curves into a front vertical section 14. The upper portion 14a of this front vertical section then inclines toward the rear until it reaches the 70 proper level for a sitter's arm, where it bends into a horizontal section 16 upon which a padded or upholstered arm rest B may be secured. The rod then bends sharply upward and extends as a rearwardly inclined section 18 to the level of the 75 top of the back. There the rod has a return bend 20 and this is followed by a section 22 extending downward and somewhat forward to somewhat below the level of the horizontal arm section 16, where the rod is preferably inclined more toward 80 the front as at 22a. The rod then curves into the final horizontal section 24 which extends forward to close by the vertical front section 14.

These side frame members A may be secured together in numerous ways. In the chair of Figures 1 to 3 inclusive I provide a front support consisting of a rod C bent as an inverted U with its depending legs c attached to a portion of each vertical front section 14 of the side frame members. These depending legs of the U-shaped 90 members constitute the front feet of the chair. The rearmost inclined upper sections 22 of the side frame members may be secured together by a metal plate D which can either be permanently attached thereto as by welding or removably attached by bolts or suitable screws. A similar metal plate E joins the final horizontal sections 24 of the side frame members, either permanently or removably.

The side frame member shown in Figure 4 is 100 not materially different from that just described. The only difference is that the horizontal arm rest section 16' is continued farther to the rear before curving into an upwardly inclined section 18', and the return bend 20' at the top of the back 105 is forward instead of rearward so that downwardly extending section 22' is at the front. The back plate D is attached to these front sections 22' instead of the rearmost pair as in Figure 3.

The chair of Figures 1 to 4 is shown with back 110

5 cushions F and seat cushions G mounted on the back and seat plates respectively, in the manner disclosed in my Patent No. 1,860,381 granted to me on May 31, 1932 for improvements in upholstered chairs, but this is merely representative as the chair can have any form or style of cushions or upholstering or none at all if that be preferred.

10 When a person sits in the chair his weight is primarily imposed on the seat and thus on the horizontal sections 24 of the side frames. The imposition of this weight causes these final horizontal seat sections to move downward. There is, of course, a marked tendency to bend or swing these seat members and this tendency is transmitted to the most rearward vertically inclined sections 22 of Figure 3 (or the front vertically inclined sections 22' of Figure 4) and these latter sections swing backward to some extent. But these sections in turn transmit the load by way of 15 the return bend to the other vertically inclined sections 18 (18') extending from the return bend to the horizontal arm sections 16 (16'). These last mentioned vertically inclined sections also bend rearward slightly and the arm sections in turn are tilted slightly downward. The final yield of the side frame members is experienced in the inclined portion 14a of the front vertical sections 14.

20 Since the side frame members are made of 50 spring steel or the like, the resistance offered by each successive section and bend of the frame, from the final horizontal side sections to the front vertical sections, counterbalances the weight of the sitter and he finds himself "floating", as it were, on the chair. He arrives at this most comfortable state with no jar or sudden stoppage, but with a most pleasant sort of resilient resistance. The slightest change in his weight, as by pressing with one or both feet on the floor, elicits a 25 corresponding reaction by the chair and the sitter has much the same sensation of buoyancy as is experienced by a swimmer in the water. It is not an exaggeration to state that it is an entirely different sensation than has heretofore been enjoyed from just sitting in a chair.

30 The same features of the yieldable frame are present in the office chair shown in Figures 6 and 7. In this arrangement the initial horizontal sections 12a of the side frame members are attached to a plate member H suitably mounted on a supporting base, generally designated by the reference letter I, which permits the seat and back to rotate and also tilt or swing backward and forward as is customary in office chairs. 35 From each initial horizontal section 12a attached to the plate member H the side frame member is identical with that previously described in connection with Figures 1 to 3, and the back and seat plates, with cushions, are similarly provided.

40 In the chair of Figures 8 to 10, there is a slight modification in the side frame members to permit relative adjustment of the back of the chair. As here shown the initial horizontal section 12, the vertical front section 14 and the arm section 16 are as shown in the chair of Figures 1 to 3. But instead of the side frame members bending upward at the rear of the arm sections they turn vertically downward into a vertically inclined section 22" and then curve into the final horizontal sections 24 to which the seat plate E is attached. The back F" of this chair has an inverted U-shaped frame member J, with the ends of its legs j pivotally connected as at p to the side frame members close by where they

50 finally bend into the horizontal seat sections. Part way up each leg j of the back frame member is a pivotally attached link K which extends into the arm rest B'. Inside this rest is opposed channel plates L provided with ratchet teeth l adapted to be engaged by a pin k carried by the link. By these means, the back can be tilted with respect to the seat at any desired angle.

55 The chair disclosed in Figures 8 to 10 is particularly adapted for use in beauty parlors, barber shops, dentists' offices, and the like, where the sitter may desirably be placed in a semi-prone position. But the chair is equally usable in the home where an adjustable inclination of the chair back is preferred. While the buoyant-like effect of the chair frame shown in Figures 1 to 7 inclusive, is not experienced to the same extent with the modified form of frame shown in Figures 8 to 10, it is nevertheless quite appreciable to the sitter, and it can be substantially realized in full by making the frame members of the chairs of Figures 8 to 10 of somewhat lighter and more resilient material.

60 It is to be understood that the so-called tubular frame member may be made from solid rod stock, or tube stock, or stock of various shapes in cross section, provided that when bent or shaped in accordance with the principles of this invention the final effect is one of resilient resistance.

105 I claim:

1. In a chair structure, a continuous flexible side frame member providing in sequence a vertical section, a horizontal arm section, a connecting section having a portion extending below said horizontal arm section, and a horizontal seat section extending from said portion parallel to and below said horizontal arm section; the said sections being so disposed that weight imposed upon the seat section is transmitted solely through the member to the said vertical section. 110

2. In a chair structure, a continuous flexible side frame member providing in sequence a vertical section, a horizontal arm section, an upwardly inclined section, a return bend at the top of the last said section, a downwardly inclined section, and a horizontal seat section. 115

3. In a chair structure, a pair of continuous flexible side frame members, each providing in sequence a horizontal section, a vertical section, an intermediate horizontal section, a connecting section having a portion extending below said intermediate section, and a final horizontal section extending from said portion; another frame member joining the said vertical sections; and a seat member joining the said final horizontal sections. 125

4. In a chair structure, a pair of continuous flexible side frame members each providing in sequence a vertical front section, a horizontal arm section, a vertically inclined section terminating in a return bend, another vertically inclined section and a final horizontal section; a seat member joining the said final horizontal sections; a back member joining one pair of the vertically inclined sections; and means for supporting the side frame members in upright positions. 135

5. A chair comprising a base; a supporting member pivotally mounted on the said base; a pair of continuous tubular side frame members each mounted on said supporting member and having in sequence a vertical section, a horizontal arm section, a vertically inclined section terminating in a return bend, another vertically inclined section and a final horizontal section; a 145

seat member joining said final horizontal sections; and a back member joining a pair of said vertically inclined sections.

6. In a chair structure, a pair of continuous flexible side frame members each providing in sequence a vertical section, an arm section, a connecting section having a portion extending below said arm section, and a final section extending from said portion toward the said vertical section; a seat member joining the said final sections; a back member pivotally mounted on the said side frame members; means for securing said back member in adjusted position; and means supporting the side frame members in upright position.

10 7. A chair comprising a side frame member formed from a piece of tubular stock which provides in sequence a vertical section; means supporting the vertical section at its lower end; an arm section extending substantially horizontally from the upper end of said vertical section; and a third section extending from the end of said

arm section and terminating close by but separated from said vertical section, with a portion of the said third section parallel to and below the level of said arm section and adapted to support a seat; the said sections being so disposed that weight imposed upon the said portion is transmitted through the said sections successively to the vertical section.

15 8. A chair comprising a side frame member formed from a continuous piece of tubular stock which provides in sequence a vertical section; means supporting the vertical section at its lower end; an arm section extending from said first section; and a third section extending from said arm section with a portion extending parallel to the arm section and below the level thereof toward the first said section and terminating short thereof; the entire side frame member being so disposed that weight imposed upon the last said section is transmitted solely through the arm section to the first said section.
